ELECTRIC HOIST

Richard E. Ten Eyck, Wichita, Kans., assignor to Duff-Norton Company, Inc., Charlotte, N.C., a corporation of Delaware

Filed July 25, 1969, Ser. No. 18,417

Term of patent 14 years

Int. Cl. D12—5

U.S. Cl. D41—1

FIG. 2

FIG. 3

FIG. 6

FIG. 4

FIG. 5

FIG. 7

FIG. 1 is a perspective view of an electric hoist embodying the new design;

FIG. 2 is a front elevational view thereof in reduced scale;

FIG. 3 is a top view of the front view shown in FIG. 2;

FIG. 4 is a rear view of the electric hoist shown frontally in FIG. 2;

FIG. 5 is a bottom view of the electric hoist shown in FIG. 2 in front elevation;

FIG. 6 is an end view of the electric hoist shown in FIG. 2 taken from the right end portion thereof;

FIG. 7 is an end view of the electric hoist shown in FIG. 2 taken from the left end thereof.

I claim:

The ornamental design for an electric hoist, as shown.
